UNITED STATES PATENT OFFICE.

THOMAS M. LAMBETH, OF SEATTLE, WASHINGTON.

AUTOMATIC OIL BURNER.

Application filed May 8, 1926. Serial No. 107,583.

My invention relates to an improvement in oil burners and has for its object the general simplification in arrangement and in adjustment of the various parts of the burner, and particularly with relation to the adjustment of an oil or steam valve relative to the other and relative to a control means, such as a pressure-operated piston.

A further object lies in the simplification of the connections between the various parts whereby the oil and steam valves can be positively and simultaneously controlled through a single member connected to a control member.

Other objects, particularly such as relate to structural improvements, will be found in a study of the accompanying drawings, wherein my invention is shown in a present preferred embodiment, and of this specification, and the claims terminating the same, wherein the features forming my invention are defined.

Figure 1 is a plan view of my burner with parts broken away and shown in section, and with parts omitted to show the interior construction.

Figure 2 is a typical section transversely of a valve port, taken on the line 2-2 of Figure 1; and Figure 3 is a similar section on the line 3-3 of Figure 1.

The burner to which my invention pertains is of the type employing steam or a mixture of steam and air to induce movement of the oil and to mix therewith. A suitable mixing device preferably forms part of the burner tip, and inasmuch as my invention is particularly directed to the means whereby the relative amounts of oil and steam are controlled, the mixing chamber and burner tip have not been illustrated herein. To control the oil and steam, I employ chambers 1 and 2, respectively, made up after the fashion of valve chests. Each of these chambers is provided with an inlet port and an outlet port, and as these are identical in each chamber, a description of one will suffice for the other. For example, the oil chamber 1 is shown as having an aperture 10 threaded to receive an outlet pipe 11 and the aperture 10 communicates with a port 12 in the bottom of the chamber 1, and preferably triangular in shape, as is best seen in Figure 1. The inlet comprises merely a tapped hole 13 in the cover 14 of the chamber, in which a pipe 15 is threaded. The outlet pipes 11 from both the steam chamber 2 and the oil

chamber 1 connect to the mixing chamber of the burner tip. It will be obvious that the inlet pipe and outlet pipe in either or both chambers, might be reversed, that is, the pipe 11 might be the inlet and the pipe 15 might be the outlet of the chambers.

To control the flow of the respective fluids, steam and oil, through the chambers, valves are provided within these chambers and co-operate with the ports 12 therein. These valves are alike in the two chambers and comprise essentially a flat valve member 3 or 3' having ears 31 upstanding therefrom, and apertured to receive a stem 4 which may slide freely through the apertures in the ears. The stem 4 extends through the chambers 1 and 2 and through the ears 31 in the valves therein, and projects beyond the chambers for a purpose which will appear hereafter. Thus the same stem 4 is connected to both the oil and the steam valves. The means of connection preferably varies, one of the valves, the oil valves for example, having a split collar 32 clamping tightly upon the stem and placed between the ears 31 of the valve. The stem 4 may be reduced, as indicated at 43, if desired, in order to more definitely position the split collar 32 and to insure its hold on the stem.

The connection at the steam valve 3' is similar to that described, except that a split nut 33 is employed in place of the split collar 32, but located between the ears 31 of the valve and connected as by bolts 34 to be non-rotative relative to the valve. The stem is threaded as shown at 42 whereby upon rotation of the stem (the split nut 33 being non-rotative) the steam valve 3' can be adjusted lengthwise of the stem. To enable engagement of the stem to turn it, one of its projecting ends may be squared as indicated at 41, enabling it to be engaged by a wrench or like device. Rotation of the stem will not affect the oil valve 3, inasmuch as the split collar 32 will permit it to rotate relative to the valve 3, but will maintain the valve 3 at a given position lengthwise of the stem.

Preferably means are provided tending to hold the valves in open position. Such means may be conveniently associated with one of the projecting ends of the stem, and as shown herein, comprise a yoke 44 apertured to receive the stem 4 and bearing upon a collar 45, secured to the stem, the yoke 44 being guided upon two or more guide bolts 46 secured in a flange 51 of the main casting

5. By means of this arrangement, the stem 4 may be rotated without disturbing the yoke 44. Between the yoke 44 and a connecting bar 47, which may provide an outboard 10 guide 48 for the stem, are positioned compression springs 49, which, bearing upon the yoke 44, tend to move the stem 4 to the right, as seen in Figure 1, and consequently to retain the valves in open position. Adjustment of tension on the springs 49 may be obtained by adjusting nuts 40 on the ends of the guide bolts 46. It will be obvious, of course, that any other suitable means for obtaining the desired result may be employed, 15 it being desirable that the spring tension means be connected as directly as possible to the projecting end of the stem 4, for it is an object to simplify the construction and to maintain the parts, so far as is possible, associated directly with a single stem, which, 20 by its movement, controls the position of the valves.

In furtherance of this object, the control means may be associated with the oppositely 25 projected end of the stem. Preferably these are automatic control means, operable by variations in the pressure of steam in the boiler which is heated by means of the burner, or by variations in the throttle line from such 30 a boiler. Such automatic means can be arranged to oppose the springs 49, whereby when the steam pressure rises, the action of the pressure controlled automatic control means tends to close the valves and thus to 35 cut down the heat of the fire; and conversely, when the pressure drops the springs tend to overcome the pressure control and to open the valves.

Such an automatic control is shown best 40 in Figure 1, and as shown comprises a piston 6 secured upon a reduced end 64 of the stem 4, and held in place by a nut 60. It is essential that the entire piston rotate upon rotation of the stem 4, in adjusting the valve 3', 45 or that the stem be swiveled in the piston, as shown herein. This piston is movable within a cylinder 61, secured by bolts 62, which likewise retain a cover 63, to a second flange 52 of the main casting 5. A steam pressure 50 pipe 65, secured in the cover 63, may be connected to a source of steam pressure as, for example, with the boiler or with the steam line, and in this manner variations in the steam pressure will be communicated, 55 through their action on the piston 6, to move the valves 3, and 3'.

It will be observed that the chambers 1 and 2 are formed in separated boxes 54 and 55 respectively, formed integral with the main casting 5, and with covers 14 secured thereon by means of stud bolts 56 received in the main casting and receiving clamping nuts 57 to hold on the covers. By separating the two chambers 1 and 2, it is possible to 60 employ packing glands 58 about the stem 4

and to have access to each packing gland independently of the others for adjustment or renewal. Further, all parts of the burner are in alignment along the axis of stem 4, and all parts are directly connected to the same stem. By simple rotation of the stem, the relative proportions of oil and steam can be varied, yet this rotation does not affect the connection of any part save the valve intended to be adjusted. Further, the valve to be adjusted may be either the steam valve, as described herein, or the oil valve.

What I claim as my invention is:

1. In an automatic oil burner, in combination, casings defining separated oil and steam chambers, and a control chamber, said oil and steam chambers each having inlet and outlet ports, a valve in each of said oil and steam chambers controlling the passage of oil or steam therethrough, a pressure-operated control element in said control chamber, and a single continuous stem passing through the several chambers, and operatively connected to said valves and to said control element to shift said valves upon movement of the control element, said stem projecting from said chambers, and means operable upon rotation of said stem for adjustment of one only of said valves relative to its port and independent of the other valve.

2. In an oil burner, in combination, casings defining separated oil and steam chambers each having inlet and outlet ports, a valve in each chamber co-operating with a port therein to control the passage of oil or steam therethrough, a single continuous stem extending through the oil and steam chambers, said stem being connected to one of said valves for free rotation, and being threaded in the other, and means operatively connected to said stem to shift the two valves simultaneously, and permitting adjustment of the threaded valve relative to its port and independent of the other valve.

3. In an oil burner, in combination, a base having formed thereon independent oil and steam chambers, each having an inlet and an outlet port, a stem passing through both chambers and projecting at opposite ends, a valve within each chamber operatively connected to the stem and controlling the passage of fluid through its respective chamber, a flange upstanding at one end of said base and apertured to receive the stem, parallel guide bolts received in said flange, a yoke operatively connected to reciprocate with said stem, and guided in said guide bolts, springs associated with said yoke and tending to move said stem in a direction to open the valves, and control means associated with said stem and normally tending to move the stem in the opposite direction.

4. In an oil burner, in combination, a base having formed thereon separated oil and

steam chambers, each having an inlet and an outlet port, a stem passing through both chambers and projecting at opposite ends, a valve within each chamber operatively connected to the stem and controlling the passage of fluid through its respective chamber, a flange upstanding at one end of said base and apertured to receive the stem, parallel guide bolts received in said flange, a yoke 10 apertured to receive said stem, and guided upon said guide bolts, a collar secured upon said stem, said yoke bearing thereon, compression springs between the outer ends of said bolts and said yoke, and tending to move said stem in a direction to open the 15 valves, one of said valves being threaded upon said stem to be adjustable lengthwise thereof upon rotation of the stem, and said stem being adapted for engagement for rotation, and control means swiveled upon the 20 opposite end of said stem from the springs, and normally tending to move the stem and valves in opposition to the springs.

Signed at Seattle, King County, Washington.

THOMAS M. LAMBETH.
